PAGE 3

FIG. 1 is a perspective view of a coffee maker embodying our design.

FIG. 2 is a side elevation view of the coffee maker.

FIG. 3 is a top plan view of the coffee maker.

FIG. 4 is a front elevation view of the coffee maker.

FIG. 5 is a rear elevation view of the coffee maker.

The dominant features of the design reside in the portions shown in full lines.

We claim:

The ornamental design for a coffee maker or similar article, substantially as shown and described.
